UNITED STATES PATENT OFFICE.

NORMAN C. SHATZER, OF ZULLINGER, PENNSYLVANIA.

PUZZLE.

1,209,048.

Specification of Letters Patent. Patented Dec. 19, 1916.

Application filed April 6, 1916. Serial No. 89,423.

To all whom it may concern:

Be it known that I, NORMAN C. SHATZER, a citizen of the United States, residing at Zullinger, in the county of Franklin and 5 State of Pennsylvania, have invented certain new and useful Improvements in Puzzles, of which the following is a specification.

This invention relates to puzzles and more 10 particularly to puzzles of that type comprising a plurality of initially interlocked members capable of manipulation to cause their separation.

It is well known that it is the habit of 15 mother woolly opossums to carry their young upon their backs, the tails of the young being entwined about the tail of the mother and the present invention contemplates forming the two members comprising 20 the puzzle, one to represent the mother opossum and the other one of the young opossums, the tails of the figures being initially interlocked and the members being so constructed that by proper manipulation the 25 tails may be separated.

In the accompanying drawings: Figure 1 is a view representing the relative positions which the members are first caused to assume in solving the puzzle; Fig. 2 is a 30 similar view illustrating another position which the members are caused to assume; Fig. 3 is a similar view illustrating a further position of the members; Fig. 4 is a similar view illustrating the positions of 35 the members immediately prior to their relative separation; Fig. 5 is a plan view illustrating a modified form of one of the said members.

Corresponding and like parts are referred 40 to in the following description and indicated in all the views of the accompanying drawings by the same reference characters.

That one of the members which is intended 45 to represent the mother opossum is indicated in general by the reference character A and the member which represents the young opossum is indicated by the reference character B.

In that form of the invention shown in 50 Figs. 1 to 4 inclusive, both members are formed from wire, but in the form shown in Fig. 5, which figure illustrates a plan view of the member which represents the mother opossum, the said member is formed 55 from sheet material. When the members

are formed from wire each member is formed from a single length of such material, and by reference to Figs. 1 to 4 inclusive, it will be observed that the member A is bent to the general outline of an opossum with the tail curled over the back, the tail being in the nature of a two strand loop indicated by the numeral 1 and in this particular form of the invention the portion comprising the outline of the back passes 60 through the bight of the said loop. As stated, in that form of the invention shown in Fig. 5 the member is formed from sheet material and the tail loop is indicated at 1^a and is formed by punching or cutting out a 65 portion of the sheet.

The member B which represents the young opossum is in all forms of the invention formed from a single length of wire which near one end is bent to represent the nose of 70 the animal as indicated at 2 and adjacent the bend is looped or twisted to represent the eye as indicated at 3 and again as indicated at 4 to represent one of the ears. Beyond the portion 4 the wire is extended 75 to form a portion 5 representing the outline of the back and the wire beyond the portion 5 is bent to form a loop 6 which constitutes one side of the tail loop of the member. At the end of the side 6 the wire is bent to form 80 the bight 7 of the loop this bight receiving the portion 5 which constitutes the back of the member. In forming the bight, and in bending the wire beyond the bight to correspond to the side 6, the other side 8 of the 85 said loop is formed and this side is continued to represent one of the rear legs of the animal as indicated at 9 and thence to represent the outline of the belly of the animal as indicated at 10 and further to represent 90 one of the forelegs as indicated at 11, the wire terminating shortly in advance of the said foreleg 11 and this and the first mentioned end of the wire being slightly spaced to provide a gap or opening 12 representing the mouth of the animal.

Initially the tail loops of the two members are interlocked and, as before stated, by proper manipulation of the members the tail members may be relatively separated.

The first step in solving the puzzle is clearly shown in Fig. 1 of the drawings and while the puzzle may be solved by holding either of the members stationary and manipulating the other member or by simultane-

ously manipulating the two members, in the solution illustrated the young opossum or, in other words, the member B is held stationary in the left hand and the member A alone 5 is manipulated. As stated, Fig. 1 represents the first position which the members are caused to assume and in this position the member A is inverted and what is then the lower portion of the tail loop of this member 10 will be located at the far side of the front of the tail member B and the rear portion of the tail loop of the member A will be located at the near side of the upper portion of the tail loop of the member B. With the 15 parts in this position the member A is swung downwardly and slightly tilted rearwardly or, in other words, toward the person manipulating the member until the narrow end of the tail loop 8 passes over the nose 2 of the 20 member B after which the tail loop of the member A is moved upwardly through the gap 12 and the member A is positioned relative to the member B as shown in Fig. 2 of the drawings in which position the tail loop 25 of the member A will be located at the far side of the side 6 of the tail loop of the member B adjacent its juncture with the back 5 of the said member and at the same time the tail loop of the member A will be at the 30 near side of the upper portion of this said side of the tail loop of the second mentioned member. With the parts in this position the member A is swung upwardly and to the left about its tail loop as a pivot and is at the 35 same time given a complete turn forwardly until the tail loop of the said member A seats in the bight 7 of the tail loop of the member B as shown in Fig. 3 of the drawings. The member A is then shifted bodily 40 forwardly so as to pass its tail loop over the nose 2 of the member B and the said member A is then shifted bodily to the left and thence forwardly so as to pass its tail loop over the loop defined by the side 6 of the tail 45 loop of the member B whereupon the tail loop of the member A will be located between the sides 6 and 8 of the tail loop of the member B as illustrated in Fig. 4 of the drawings and the members may be then bodily separated by moving the member A to the 50 right and the member B to the left.

Having thus described the invention, what is claimed as new is:

1. A puzzle of the class described including members having loops designed to be initially interlocked, one member being of skeleton formation and its loop comprising sides connected at one end of the loop by a bight receiving one side of the open body 55 portion of the member, the said side of the body portion constituting a continuation of one side of the said loop, and another side of the said body portion constituting a continuation of 60

tinuation of the other side of the loop, the body portion being provided with a gap. 65

2. A puzzle of the class described including members having loops designed to be initially interlocked, one member being of skeleton formation and its loop comprising sides connected at one end of the loop by a bight 70 receiving one side of the open body portion of the member, the said side of the body portion constituting a continuation of one side of the said loop, and another side of the said body portion constituting a continuation of 75 the other side of the loop, the body portion being provided with a gap, the loop of the other member being of a diameter to permit of the passage of either side of the same through the said gap while the loops are 80 mutually engaged.

3. A puzzle of the class described including members having loops designed to be initially interlocked, one member being of skeleton formation and its loop comprising 85 sides connected at one end of the loop by a bight receiving one side of the open body portion of the member, the said side of the body portion constituting a continuation of one side of the said loop, and another side 90 of the said body portion constituting a continuation of the other side of the loop, the body portion being provided with a gap, the loop of the said member being located at one end of the said member and the gap near 95 the other end thereof and the loop of the other member being so proportioned as to permit of passage of the loop over the last mentioned end of the first mentioned member and through the said gap while the loops 100 are mutually engaged.

4. A puzzle of the class described including members having loops designed to be initially interlocked, one member being of skeleton formation and its loop comprising 105 sides connected at one end of the loop by a bight receiving one side of the open body portion of the member, the said side of the body portion constituting a continuation of one side of the said loop, and another side of 110 the said body portion constituting a continuation of the other side of the loop, the body portion being provided with a gap, the loop of the said member being located at one end of the said member and the gap near the 115 other end thereof and the loop of the other member being so proportioned as to permit of passage of the loop over the last mentioned end of the first mentioned member and through the said gap while the loops 120 are mutually engaged, and being further so proportioned as to permit of its passage over the loop formed by one side of the loop of the first mentioned member.

In testimony whereof I affix my signature. 125
NORMAN C. SHATZER. [L.S.]
